J. DURELL GREENE, OF CAMBRIDGE, ASSIGNOR TO HIMSELF AND
CHARLES H. P. PLYMPTON, OF BOSTON, MASSACHUSETTS.

Letters Patent No. 88,781, dated April 13, 1869.

IMPROVEMENT IN ANCHORS.

The Schedule referred to in these Letters Patent and making part of the same.

To all whom it may concern:

Be it known that I, J. DURELL GREENE, of Cambridge, in the county of Middlesex, and State of Massachusetts, have invented an Improved Anchor; and I do hereby declare that the following, taken in connection with the drawings, which accompany and form part of this specification, is a description of my invention, sufficient to enable those skilled in the art to practise it.

This invention relates to peculiarities in anchors using no stock, and in which two flukes, or arms are pivoted to the anchor-shank, so that, in taking ground, both flukes will form equal angles with the shank, and on the same side thereof, the flukes turning to either side of the shank as the anchor touches the ground.

My invention may be said to consist in an anchor made with the palms of its flukes in the same plane, and with the arms of its flukes made integral with an open yoke, across which extends, from one side to the other, in the same plane with the palms and arms of the flukes, a pin, shaft, or pivot, integral with the yoke, the shank being entered within the yoke-opening, and grasping the cross-shaft in the yoke, in the manner of a machine-bearing, all of which will be fully understood from inspection of the drawings, in which—

Figure 1 is a side elevation of an anchor made in accordance with my invention, about as it appears when it has "taken hold."

Figure 2 being a sectional view of the same, but with the shank horizontal.

Figure 3 being a plan of my anchor as it appears when resting on deck.

a is the shank, which is without a stock, as none is needed in my anchor, the shank being provided with a cable-ring, *b*.

There are two flukes, each made up of a palm, *c*, and arm *d*, located in the same plane, the arms being made integral with a central piece, *e*, which, being made open, and joining the arms together, and fitting over the shank, which is thrust through the opening in *e*, I call a yoke.

Across this opening, and in the same plane with the arms *d*, is a cylindrical pin, *f*, integral with the yoke.

The end of the shank making the crown of the anchor is slotted through, leaving, at the bottom of the slot, one-half of a cylindrical bearing, of a diameter suited to the pin *f*, and between the jaws *g*, formed on each side of the slot through the shank, is fitted a cap-piece, *h*, which has a semi-cylindrical cavity at its inner end, which fits upon the pin *f*, and completes the bearing by which the flukes are held to the shank, and

on which they pivot in turning to one or the other side of the shank.

This cap-piece is held in the jaws *g* by a bolt, *i*, passing through the cap, *h*, and jaws *g*, in a plane at right angles to the axis of pin *f*.

In the outer end of cap, *h*, is a hole, *j*, parallel with the pin *f*, the purpose of said hole being for attachment of a buoy-rope, when necessary, and also for attaching the fish-tackle.

The pin *f* is preferably fitted somewhat loosely in its bearing, and receives none of the pull of the vessel upon the anchor, this pulling-strain being taken by the yoke and the shank at their points of contact, denoted by *z z* in fig. 2. When the anchor falls on the ground flatwise, as in fig. 3, it is clear that any pull on the cable will cause the shank to assume the angle, with relation to the flukes, seen in fig. 1, the limit of the angle being determined by the relation of the points of contact *z z*.

Of course it will be obvious, that when the anchor assumes such a position, any obstruction to the drag of the anchor-bills *k* will cause them to catch, and the palms and flukes will plow into and will bury themselves in the ground.

If the anchor, in falling, strikes upon the edge, *l*, of either palm, it will tip over, so that the palms will form an angle of about forty-five degrees with the ground, this bringing the crown of the yoke into contact with the ground at one of the points *z z*, and then any drag upon the anchor will bring both bills to the ground, so that, when they meet with resistance, they and the flukes will bury, and the shank will take the angle seen in fig. 1.

When dismembered by removal of cap, *h*, the parts of the anchor stow closely, and, spare parts being carried, breakages may be easily repaired, or when two or more anchors of the same size are carried, the broken portion of one may be replaced by a whole part from another.

The hole *j*, besides serving for the purposes named before, is intended to receive a tripping-line, the purposes and operation of which are too well known to seamen to need explanation here.

I claim the anchor, substantially as made, with the palms and arms of the flukes in the same plane, united by the yoke, as shown, with the shank extending through the yoke, and pivoted thereto, as set forth.

J. DURELL GREENE.
